[57] **CLAIM**

The ornamental design for a tweezer, as shown and
described.

DESCRIPTION

FIG. 1 is a perspective view of a tweezer showing my
new design;

FIG. 2 is an elevational view of one side thereof, the
other side being substantially identical thereto;

FIG. 3 is a top plan view of the tweezer, the bottom
being identical thereto;

FIG. 4 is an elevational view of one end of the tweezer;
and

FIG. 5 is an elevational view of the opposite end
thereof.

Fig. 1.

Fig. 2.

Fig. 3.

Fig. 4.

Fig. 5.
